UNITED STATES PATENT OFFICE.

FREDERICK H. P. FICKEISSEN, OF NEW YORK, N. Y.

RAZOR.

1,125,996.

Specification of Letters Patent.

Patented Jan. 26, 1915.

Application filed October 17, 1913. Serial No. 795,661.

To all whom it may concern:

Be it known that I, FREDERICK H. P. FICKEISSEN, a citizen of the United States, and a resident of Richmond Hill, Long Island, in the city of New York, county of Queens, and State of New York, have invented certain new and useful Improvements in Razors, of which the following is a specification.

10 This invention relates to razors, and more particularly is intended to embody improvements therein, which make the usual razor entirely safe in its operation, or make a safety razor much like the usual or ordinary 15 razor.

The invention will be more fully described hereinafter and finally pointed out in the claims.

In the accompanying drawing, Figure 1 20 is a perspective view of a razor showing my invention embodied therein, Fig. 2 is a top view of the same, Fig. 3 is a view of the other side of the razor from that shown in Fig. 1, Fig. 4 is a vertical transverse section 25 taken on line 4—4 of Fig. 3, and Fig. 5 is a view with the parts in open position.

Similar reference numerals indicate corresponding parts throughout the several figures of the drawing.

30 Referring to the drawing, and more particularly to Fig. 1, the handle 10 is of any suitable material, as celluloid, ivory, or the like, and is pivoted at 11 to the tang 12. The tang consists of two parts arranged 35 parallel with each other, as shown in Fig. 2, one part, which is indicated by 13, being provided with a holding portion 14, arranged at each end of the blade-holding member, and the other part of which is provided with an upset portion 15. The member 13 has also side-holding pieces 17, which embrace the other tang member 16.

Intermediate the member 13 and the member 16, a flat blade 20 is arranged, which has 45 its cutting edge held between the end members 14, and which has its back pressed by the upset portion 15.

By the device described, the blade 20 may be readily supported in position between the 50 two tang members 13 and 16, and the corner edges of the blade may be readily protected by the protecting members 14, while the back portion 15 serves to press and hold the blade

in position. The two parallel tangs readily permit the withdrawal of the blade, and the 55 substitution of a new one, and the protecting corners provide means for safe-guarding the user from injury, while the two blade-holding members permit the blade to extend therethrough, and cause an efficient 60 cutting surface to be presented. The blade-holding portions are beveled off as indicated by 22 and 23, and the cutting edge portion of the blade indicated by 24 in Fig. 4 extends beyond the beveled off portions 22 65 and 23.

Another advantage of my improvement is that the razor may be stropped and wiped without taking the blade away from the 70 holder.

The blade extends beyond the blade-holders about a sixteenth of an inch all along the length of the blade-holders and is entirely free along its length excepting that it has at its corners, the guard members described, to protect the user from being cut. This is entirely new in the use of the ordinary open edge razor. The opening of the blade-members permits a ready substitution 75 of the blades. The blade also extends 80 slightly above the blade-holders so that as the blade becomes worn by re-sharpening, the movable blade-holder may readily press downward on the blade and thus give a good surface to the user.

I have shown one embodiment of my invention, but changes may be made therein without departing from the spirit of the invention as defined in the appended claims.

I claim:

1: In a razor, the combination of plates extending substantially to the edges of the razor-blade to form a safety-guard therefor, said plates frictionally and immovably gripping said razor-blade, and having portions in front of said blade only at the corners thereof of the exposed edge of said blade being anterior the rest of the razor, save the portions of said blades at the corners thereof.

2. In a razor, the combination of plates extending substantially to the edges of the razor-blade to form a safety-guard therefor, said plates frictionally gripping said razor-blade, and having portions in front of said 105 blade only at the corners thereof, one of

said plates having an upset portion at the rear thereof at a small distance behind the rear-end of the other plate said upset portion being in contact with the back of the 5 razor-blade, whereby the razor-blade can be fed forward.

In testimony that I claim the foregoing

as my invention, I have signed my name in presence of two subscribing witnesses.

FREDERICK H. P. FICKEISSEN.

Witnesses:

F. Hogg,

T. LOWE.
